UNITED STATES PATENT OFFICE.

EDWARD B. LEARY, OF ROCHESTER, NEW YORK.

GARMENT-PRESSING MACHINE.

Application filed May 5, 1922. Serial No. 558,817.

To all whom it may concern:

Be it known that I, EDWARD B. LEARY, a citizen of the United States of America, of Rochester, in the county of Monroe and State of New York, have invented certain new and useful Improvements in Garment-Pressing Machines; and I do hereby declare the following to be a full, clear, and exact description of the same, reference being had to the accompanying drawings, forming a part of this specification, and to the reference numerals marked thereon.

My present invention relates to laundry appliances, and more particularly to pressing machines, and it has for its object to provide a simple, convenient and inexpensive appliance of this kind that will be particularly useful in pressing garments such as suits of clothes, overcoats etc. The improvements are directed in part toward the relative arrangement and movements of the head and the buck whereby the operator is enabled to quickly place the garment in position and quickly remove it after it is pressed, and whereby the engagement of these parts is such as to produce uniform pressure. To these and other ends the invention consists in certain improvements and combinations of parts, all as will be hereinafter more fully described, the novel features being pointed out in the claims at the end of the specification.

In the drawings:

Figure 1 is a front view of a garment pressing machine constructed in accordance with and illustrating one embodiment of my invention;

Figure 2 is a central vertical sectional view taken in a plane from front to rear of the machine showing the parts in their normal or open positions;

Figure 3 is a view similar to Figure 2 showing the machine closed or in pressing position, and

Figure 4 is a detail section on the line 4—4 of Figure 3.

Similar reference numerals throughout the several views indicate the same parts.

In general my improved machine in its preferred form comprises a vertically swinging head that moves downwardly and forwardly to an operative position in which it is automatically locked and where it is then engaged by a vertically reciprocatable buck on which the garment has been spread. The actuating means for the buck is adjust-

able to various throw and a single operating means successively operates the head actuating mechanism and the buck actuating mechanism, the operating means being pneumatic.

Referring more particularly to the drawings, 1 indicates a suitable frame having forwardly extending side rails 2 supporting a light table 3 preferably composed of wooden slats that are merely sufficient to prevent the garments from falling or hanging down into the moving parts. Upwardly extending arms 4 at the rear support a shaft 5 upon which swings vertically a bell crank lever 6 that is double or yoke shaped so that a forward arm 7 of the bell crank is attached at each end of the head 8 carried thereby. This head 8 and its cooperating buck 9 may be of any desired character. One or both is usually padded and supplied with steam by which it is heated and moistened as is well known in the art, but this invention has nothing to do with these elements specifically and no steam connections are herein shown.

A rearward arm 10 of the bell crank is connected by a link 11 pivoted thereto at 12 to an arm 13 of a bell crank lever 14 turning on a shaft 15 in the frame which arrangement will be seen to constitute a toggle adapted to operate the arm 7 and head 8 from the inoperative raised position of Figure 2 to the operative pressing position of Figure 3 when the forwardly extending arm 16 of the bell crank 14 is depressed. The toggle ultimately engages a stop arm 17 on the frame which halts it in a dead center position as shown in Figure 3 and causes the head 8 not only to move to a definite operative position where it is held in a manner hereinafter described, but to be locked there prepared to resist considerable pressure.

The operating means embodies a yoke shaped pull rod 18 adapted to reciprocate vertically in a guiding cross rail 19 on the frame. Within the pull rod is a vertically sliding contact member 20 having lateral lugs 21 by means of which it is guided in slots 22 in the pull rod and also having a stem 23 extending through the head of the latter and surrounded by a coil spring 24 interposed between the head and the contact member 20 so that the latter is normally in the lowered position of Figure 2. When the rod 18 is drawn downwardly the contact

member 20 engages the bell crank arm 16 which latter extends through the yoke shaped rod and the spring 24 is of sufficient strength to cause the movement of the head 8 to operative position. This constitutes a lost motion connection between the operating mechanism and the head and its actuating devices because thereafter the pull rod 18 may continue downwardly relatively to the head actuating means because of the compression of the spring 24 as shown in Figure 3. The contact member 20 and its said spring are relieved of the function of holding the head 8 in operative position because of the dead center position of the toggle 11-13 previously described.

This lost motion connection is necessary in the present instance because after the head 8 has assumed its operative position the buck 9 is raised into pressing contact with it and a continued downward movement of the pull rod 18 is utilized to so actuate the buck. The latter is carried by a reciprocatory frame 25 guided in gibbs 26 to slide vertically on the side standards of frame 1 at the front of the machine. Extending transversely through the center of this frame and having bearings therein is a shaft 27 carrying near its ends a pair of eccentric cams 28 and provided at its center with a hand wheel 29 for adjusting these cams. The latter are engaged from below by the forwardly extending arm 30 of a yoke 31 pivoted on a transverse shaft 32 in the frame 1 while a pair of rearwardly extending arms 33 on the yoke straddle or embrace the pull rod 18 (Figure 4) beneath lateral pins 34 on the latter that are adapted to engage them.

Thus on the downward movement of the pull rod 18 after the head 8 has been actuated to operative position the pins 34 engage the arm 33 of the yoke 31 and the buck 9 is raised into pressing contact with the head while the spring 24 is compressing and the contact member 20 remains stationary against the arm 16 of the head actuating mechanism. The motion being transmitted through contact with the cams 28, these latter may be adjusted through the hand wheel 29 to extend or restrict the limit of upward movement of the buck and make the ultimate pressure greater or less as desired. The prime mover for the operating means is a pneumatic cylinder 35 supported in a central upright position at the base of the frame 1 by a bracket 36. Compressed air is admitted through a supply pipe 37 to a suitable two-way valve 38 having laterals 39 and 40 leading to ports 41 and 42 within the cylinder upon opposite sides of a piston 43. The piston rod 44 is connected to and forms a continuation of pull rod 18, and it will be understood by those skilled in the art that by operating the valve 38 through pull rods

45 and 46 connected by a bell crank 47 compressed air may be ultimately admitted to opposite sides of the piston 43 and cause the pull rod 18 to move upwardly and downwardly at will. Pull rod 46 is provided with a handle 48 operating in a slot 49 at the front of table 3 below the buck 9 and readily accessible to an operator standing at the front of the machine.

When the machine is not in use the head 75 is up and the buck is down as in Figure 2 giving a wide degree of separation which is of great convenience to the operator in spreading the garments to be pressed on the buck and the fact that the head swings upwardly and rearwardly increases the convenience in this respect. It is further to be noted that although the head swings it does not swing into pressing contact but merely to a position ready to receive the buck which 80 has a linear movement toward it and therefore engages it at all points simultaneously and with equal pressure.

I claim as my invention:

1. In a pressing machine, the combination 90 with a swinging head and a system of levers for actuating the same to a definite position including a toggle movable to a dead center that locks the head in such position, of a reciprocatory buck movable 95 against the head when so positioned, and means for successively so operating the head and then the buck comprising a pull rod connected to the system of levers and a lever actuated by the pull rod and cooperating 100 with the buck.

2. In a pressing machine, the combination with a swinging head and a system of levers for actuating the same to a definite position including a toggle movable to a dead center that locks the head in such position, of a reciprocatory buck movable against the head when so positioned, and means for successively so operating the head and then the buck comprising a pull rod connected to the 105 system of levers, a lever actuated by the pull rod and cooperating with the buck and a pneumatic prime mover acting upon the pull rod in two directions.

3. In a pressing machine, the combination 110 with a frame, a reciprocatory buck and a swinging head cooperating therewith, of a system of levers for actuating said head including a toggle, a pull rod guided in the frame and having a yielding contact member engaging the levers to operate the head to a definite position in which it is locked by the toggle assuming a dead-center position, and actuating means operated by the pull rod for moving the buck toward the 115 said position of the head while the contact member is yielding.

4. In a pressing machine, the combination 120 with a vertically movable buck, a vertically swinging head adapted to cooperate there-

with, means including a yielding contact element for operating the head to a definite engaging position and locking it there, and actuating devices cooperating with said 5 means to move the buck against the head during the yielding of said contact element.

5. In a pressing machine, a reciprocatable buck, a swinging head and means having a lost motion connection with the head for operating it to a limit of movement toward the buck and thereafter operating the buck toward the head.

6. In a pressing machine, a reciprocatable buck, a swinging head, means having a lost motion connection with the head for operat-

ing it to a limit of movement toward the buck and thereafter operating the buck toward the head and means for automatically locking the head at such limit of movement.

7. In a pressing machine, the combination 20 with a frame, a vertically and rearwardly swinging head, a vertically reciprocatable buck at the front of the frame, a vertically disposed pull rod for successively swinging the head downwardly and lifting the 25 buck into pressing relationship with the head and a vertically disposed pneumatic cylinder for operating the pull rod.

EDWARD B. LEARY.
